CURTAIN STRETCHER

Filed June 5, 1936

UNITED STATES PATENT OFFICE

2,092,953

CURTAIN STRETCHER

Clarence G. Carlson, Chicago, Ill., assignor to
 Chicago Curtain Stretcher Company, Chicago,
 Ill., a corporation of Illinois

Application June 5, 1936, Serial No. 83,623

3 Claims. (Cl. 287—99)

This invention relates to curtain stretchers employing side rails (or end rails) which are of such length that it is desirable to make them in sections in order to permit the folding of the 5 curtain stretcher into compact form when it is not set up for use. This requires that the rail sections be united in such a manner as to afford a firm and rigid connection when in use and sufficient reinforcement at the joint to prevent 10 bending or collapse, and at the same time afford means which will permit the joint to be quickly broken and which will thereafter serve to hold the two sections in folded relation to one another.

The present invention is directed to the means 15 provided for affording an interlocking connection for the rail sections of extremely simple and rugged construction, which may be manufactured by a simple punch press operation and which in use will afford abundant rigidity and at the same 20 time permit the sections to be drawn apart and folded without difficulty.

Further objects and details will appear from a description of the invention in conjunction with the accompanying drawing, wherein,—

25 Figure 1 is a plan view of a portion of the curtain stretcher showing the joint members of the present invention;

Fig. 2 is an edge elevation of the same;

Fig. 3 is a plan view showing the joint broken 30 preparatory to the folding of the rail sections;

Fig. 4 is a similar view showing the parts in 35 folded relation;

Fig. 5 is a sectional view taken on line 5—5 of Fig. 1;

Fig. 6 is a sectional view taken on line 6—6 40 of Fig. 4; and

Fig. 7 is a perspective view showing the joint plates standing in their intended relation to one another with the rail sections removed.

45 As shown in Fig. 1, the curtain stretcher of standard type is provided with side rail sections 10 and 11 which when the stretcher is set up stand in alignment with one another and with their ends in closely abutting relation. A wooden cross rail 12 traverses the joint between the wooden side rail sections 10 and 11, the cross rail being provided with the usual graduations marked thereon.

The rail section 10 has secured thereto on opposite sides a pair of locking bars 13 and 14 which 50 are secured by means of rivets 15 passing through the wooden rail section and to overlap the end of the rail section 11 when the two sections stand in butt contact. The locking bar 13 is provided near its outwardly projecting end with an open slot 16 and the locking bar 14 is of L-shape and

provided with an angular extension or leg 17 5 provided with an elongated closed slot 18 in register at its outer end with the open slot 16. A screw bolt 19 is freely entered through the rail section 11 and is provided with a head 20 which, when the rail sections are assembled as in Fig. 1, is adapted to bear against the slotted end of the locking bar 13. The bolt 19 is also entered through the wooden cross rail 12 near its end, and the threaded end of the bolt receives a wing nut 21 10 which may be turned down to abut against the cross rail 12 and hold the locking bars in tightly clamped relation upon opposite sides of the end of the rail section.

The slot 18 in the leg 17 is of sufficient length 15 to permit the bolt 19, when loosened, to be slipped to the outer end of the slot as in Fig. 3, which affords just sufficient clearance to permit the bolt to act as a hinged pintle or pivot for swinging around the side rail section 11 into parallel folded 20 relation to the section 10, and also permits a similar folding of the cross rail 12 as in Fig. 4. This permits the elongated side rails of the curtain stretcher to be folded into convenient compass 25 for storage and also insures against accidental disassembly of the parts, although permitting such disassembly by the complete removal of the wing nut 21 and bolt 19 if occasion requires.

The two locking bars 13 and 14 being stamped 30 from plate metal without offsets or protuberances may be made of comparatively heavy stock by a simple stamping operation which affords great 35 rigidity, and the connection thus afforded serves to hold the ends of the side rails into close butt contact so that a single screw bolt and wing nut will afford abundant friction to maintain the parts in aligned relation during use. This is due to the fact that the proportioning of the parts is such that the two rail sections can be brought into 40 aligned relation only by a transverse sliding movement, and the ends of the rails being cut at right angles will thus slip past one another in very close contact, so that this closeness of fit is relied upon to prevent bending or buckling at the joint, and the locking elements serve merely to 45 maintain the butt contact so that additional bracing is unnecessary.

The device is of extremely simple construction 50 and has been found distinctly superior to more complicated devices employing hinge connections or the like.

Although the connection hereinbefore described 55 possesses substantial advantages for use in locking the rail joints of a curtain stretcher, it is also

adapted for use under circumstances in which a like connection is required.

I claim:

1. In a curtain stretcher or the like, the combination of rail sections standing in end abutment with one another, one of the sections being provided on opposite sides with forwardly projecting locking bars extending past the joint between the rail sections and adapted to embrace the companion rail section, each of the locking bars being provided with a transverse slot the slots extending in parallel relation and, at least one of said slots being closed at its outer end, a connecting member entered through the two slots and through the last named rail section, and locking means on the connecting member for holding the locking bars in locked relation across the joint between the rail sections, the slots being spaced from the end of the member which carries the locking bars at a distance sufficient to prevent longitudinal movement of the sections from the position establishing close butt contact and the closed slot being of sufficient length to permit lateral movement of the rail sections and to permit the abutting ends to slip past one another to the degree necessary to permit folding of the structure.
2. In a curtain stretcher or the like, the combination of side rails normally adapted to stand in end abutting relation to one another, one of the sections being provided on opposite sides with locking bars projecting forwardly therefrom in position to embrace the sides of the companion rail section near the end thereof, one of the locking bars being provided within its projecting end with a transversely extending open slot and the other locking bar being provided with a laterally extending leg having therein an elongated slot parallel with the first mentioned slot and closed at its outer end, a bolt entered through the companion rail section and through the slots in the locking bars, and the slots being spaced from the

end of the section which carries the locking bars in a degree sufficient to prevent longitudinal movement of the sections from the position establishing close butt contact, and screw means on the bolt for holding the locking bars in clamping relation across the joint between the rail sections, the elongated slot being configured to permit the rail sections to be moved laterally and the abutting ends to slip past one another without longitudinal displacement to the degree necessary to permit folding of the structure.

3. In a curtain stretcher or the like, the combination of side rails normally adapted to stand in end abutting relation to one another, one of the sections being provided on opposite sides with locking bars projecting forwardly therefrom in position to embrace the sides of the companion rail section near the end thereof, one of the locking bars being provided within its projecting end with a transversely extending open slot and the other locking bar being provided with a laterally extending leg having therein an elongated slot parallel with the first mentioned slot and closed at its outer end, a bolt entered through the companion rail section and through the slots in the locking bars, and the slots being spaced from the end of the section which carries the locking bars in a degree sufficient to prevent longitudinal movement of the sections from the position establishing close butt contact, means on the bolt for holding the locking bars in clamping relation across the joint between the rail sections, the elongated slot being configured to permit the rail sections to be moved laterally and the abutting ends to slip past one another without longitudinal displacement to the degree necessary to permit folding of the structure, and a cross rail abutting against the outer face of the angularly disposed slot lock and having the bolt entered therethrough and adapted to pivot on said bolt to permit fold- 40

CLARENCE G. CARLSON.
